UNITED STATES PATENT OFFICE.

WINFIELD SCOTT MARSHALL, OF CENTRALIA, ILLINOIS.

CONVERTIBLE SADDLE-BAGS AND HAND-TRUNK.

SPECIFICATION forming part of Letters Patent No. 340,339, dated April 20, 1886.

Application filed January 30, 1886. Serial No. 190,345. (No model.)

To all whom it may concern:

Be it known that I, WINFIELD SCOTT MARSHALL, of Centralia, in the county of Marion and State of Illinois, have invented certain new and useful Improvements in Convertible Saddle-Bags and Hand-Trunks; and I do hereby declare the following to be a full, clear, and exact description of the invention, such as will enable others skilled in the art to which it pertains to make and use the same.

My invention relates to a device adapted to be used as a hand chest or trunk or as a saddle-bags carrier for horseback travel.

The invention consists in the various features of construction and combinations of parts hereinafter fully described, and pointed out in the claims.

In the drawings, Figure 1 represents a perspective view of my invention, the parts being adjusted to form a hand trunk or chest. Fig. 2 is a similar view showing the parts arranged to form saddle-bags. Figs. 3, 4, 5, and 6 illustrate various parts of the invention in detail.

25 A and B represent counterpart boxes or cases, adapted to receive medicine-bottles, merchandise, or other portable commodities, and as both cases are of the same construction a description of one will suffice for both.

30 C represents the back of the case.

D D are the sides braced apart by a rod, d, which is bent at right angles at each end, as shown. The interior of the case is provided with suitable compartments or holders, E, to receive whatever is to be carried.

35 F represents the front of the case, which is hinged to the bottom f, and may also be fitted with holders g, to receive different articles. This front F extends only as high as the rod 40 d, and the top G of the case, which is hinged to the upper end of the back C, overlaps the front and is to be secured thereto by a button or catch, H.

I have shown a hinged box, I, secured to the top G of the case. Said box fills the space between the rod d and the upper ends of the sides of the case.

45 It will be understood that I do not in any wise limit myself to the interior arrangement 50 of the cases A and B, as such arrangement will necessarily vary with the different uses of the device; and while I show a very con-

venient interior arrangement of holders and compartments for use when the device is to be employed as a medicine or sample case, it will 55 be obvious that where the device is to be used for other purposes different interior arrangements may be resorted to.

To the rear side of the back C of each case I secure a guide-frame, J, (preferably of 60 leather,) consisting of parallel sides j j, connected at their upper ends by a handle-strip, K, which projects above the back C, and is suitably slotted to form a handle for the case.

L represents a strap or band, the ends of 65 which are passed through the handle-openings k k, one end through each handle. To each end of this strap or band is secured a metal bar, M, which prevents the accidental disconnection of the strap from the handle. 70 As thus secured, the strap may be readily drawn through both handles until the end bars, M M, come in contact with the under edges of the strips K K, Fig. 2. The bars M M are also adapted to fit under the bottom 75 edges of the cases A and B, as illustrated in Fig. 1, when the device is used as a hand trunk or chest.

Each side of each case is to be provided with means for securing the cases together 80 when they are in the position shown in Fig. 1. I show in the drawings a hinge device, N, one leaf, n, of which is rigidly secured to the case, while the other leaf, n', overlaps the other case to rest upon a catch-plate, O, provided with pins o, which project through slots p, formed in the hinge-leaf n', after which said pins are turned to throw their lugs o' out of register with the holes p of the hinge-leaf n'.

As thus constructed, my improved device 90 is adapted to be employed either as a hand trunk or chest or carried after the manner of saddle-bags, as follows:

When it is desired to use the invention as a hand trunk or chest, the two cases A and B 95 are drawn together back to back, as shown in Fig. 1, and the cross-bars M M of the strap L are secured under the bottom edges of the cases. The strap L will fit snugly in the spaces between the sides j j of the guide and 100 handle frame J flush with said sides, thus permitting the backs of the cases to fit closely together. The catch devices on the sides of the cases are then secured, and the two han-

dles will rest opposite each other to form a convenient single handle for the trunk.

When it is desired to use the device for horseback travel, the overlapping leaves $n' n'$ 5 of the hinges are unfastened and turned back upon the fixed leaves n , and secured over catch-lugs $q q$, as shown. The cross-bars M are released from contact with the bottom edges of the cases and the strap is drawn until said bars rest below the handles, as seen in Fig. 2, thus enabling the strap to be thrown over a horse's back to suspend the cases.

It will be apparent that many changes may be made in the details of my device without 15 departing from the spirit of my invention; hence I would have it understood that I do not limit myself to the exact form of the several parts here shown, but reserve to myself the right to make all such modifications or 20 alterations as may properly fall within the scope of my invention.

Having fully described my invention, what I claim as new, and desire to secure by Letters Patent, is—

25 1. The combination, with two independent cases having handles, as described, of a strap passed through said handles and having a lon-

gitudinal sliding movement, and limited in such movement by cross-bars at its ends, substantially as set forth.

2. The combination, with two independent cases, of a sliding-strap connection, said strap having cross-bars at its ends to engage the bottom edges of the cases, substantially as and for the purpose set forth.

3. The combination, with two cases each provided with a combined guide and handle frame, of a movable strap provided with cross-bars at its ends and connected to said frames, substantially as set forth.

4. The combination, with two independent cases adapted to be secured together back to back, of handles which may be brought together to form a single handle, a sliding strap, L , and a hinge device and catch-plate to connect the cases, substantially as set forth.

In testimony whereof I have signed this specification in the presence of two subscribing witnesses.

WINFIELD SCOTT MARSHALL.
